UNITED STATES PATENT OFFICE

2,156,276

DESK STAND

Jesse L. Coen, Bluefield, W. Va.

Application November 9, 1936, Serial No. 109,955

11 Claims. (Cl. 242—107)

(Granted under the act of March 3, 1883, as
amended April 30, 1928; 370 O. G. 757)

The invention described herein may be manufactured and used by or for the Government of the United States for governmental purposes without the payment to me of any royalty thereon, in accordance with the provisions of the act of April 30, 1928 (ch. 460, 45 Stat. L. 467).

This invention relates to a desk stand consisting of a single unit adapted to perform the functions of a plurality of desk utensils, the configuration of which is claimed in my Design Patent No. 105,326.

An object of the invention is to provide a single article of manufacture which is capable of performing the functions of a desk lamp, a blotter holder and/or dispenser, a pencil sharpener, a pen and pencil tray, ink wells, paper clip tray, ash tray, a calendar stand or rack, paper weight, and so forth.

Another object of the invention is, therefore, to provide a single desk stand whereby heterogeneous desk utensils may be dispensed with.

Other objects of my invention will be set forth in, and become apparent from, the following description, it being understood that the above general statements of the objects of my invention are intended to generally explain the same without limiting it in any manner.

Equipment, arrangements, and constructions thereof, having the characteristics of the invention and by which the invention may be practiced are intended to be illustrated by the accompanying drawings in which—

Fig. 1 is a vertical cross section of my assembled stand taken longitudinally through the central portion thereof;

Fig. 2 is a plan view having a portion of a housing broken away to illustrate an interior reel;

Fig. 3, a transverse vertical cross section taken at line A—A of Fig. 1;

Fig. 4, a transverse vertical cross section taken at line B—B of Fig. 1;

Fig. 5, a plan section of sheet material attached to a reel apron;

Fig. 6, a cam and cam follower adapted to wind a spring operated reel within the desk stand;

Fig. 7, a strip of sheet material of the type to be dispensed from the desk stand;

Fig. 8, a reel apron;

Fig. 9, clamping means for attaching sheet material to the reel apron;

Fig. 10, a longitudinal vertical cross section taken at line C—C of Fig. 5;

Fig. 11, a longitudinal vertical cross section taken at line D—D of Fig. 7 of a clamp, Fig. 9, applied to the end of sheet material; and

Fig. 12, a section in perspective illustrating means for releasably gripping and holding the unreeled material against rewinding.

Several embodiments of my invention are known to me but according to that by means of which the invention may be practiced, I provide a base 15 having recesses 16 (see Fig. 2) adapted for use as ink wells or as means for receiving ink wells; as containers for paper clips and the like or as means for retaining clip bowls; and as ash receivers or as means for receiving ash trays. The base is also provided with elongated depressions 17 (see Fig. 3) adapted for use as retainers for pens and pencils.

Upon the base 15 is mounted a housing, one portion 19, of which is adapted to operably retain and house a pencil sharpener 20, and another portion, 21, of which is adapted to operably contain a spring rewind reel 22. The portion 21 is attached by suitable fastening means 22a to the base 15 and carries the portion 19 in axial alignment at one end.

Upon housing 21 is mounted a lamp shade 23 which projects over housing 19 and is provided with a socket 24 to which a light bulb 25 may be operably connected. The socket is operably connected to an electrical conduit 26 which preferably, but not necessarily, passes from within the shade 23, into and through housing 21, and thence passes into and extends from the base 15 for connection to a source of electrical power.

The extreme ends of housings 19 and 21 are provided with end closures 27 and 28, respectively, the end closure 28 on housing 21 being removably retained by means of key-hole type bayonet slots 29, provided therein, which engage screws 30 protruding from the edge of housing 21. Housing 19 is also removably attached to housing 21 by similar screws and bayonet slots provided on the abutting ends 31 and 32, respectively, of the housings.

Housing 19 is provided with the conventional window opening whereby pencil shavings may be removed, the edge of the opening being provided with a bracket 33, or other suitable means, for slidably receiving and engaging a transparent closure member.

The end closures 27 and 31, of housing 19, are provided with bearings 34 and 35 wherein the shaft, 36, of the pencil sharpener 20 is operably mounted. The shaft portion which operates in bearing 34 is, of course, hollow and adapted to receive a pencil for sharpening, and the end of the shaft portion which operates in bearing 35 is provided with a groove 37 whereby the shaft 36 may be engaged by a tongue on driving mechanism to be described hereinafter. The shaft 36 is also provided with a shoulder 38 so positioned as to permit a slight longitudinal shaft movement (the purpose of which is to be described hereinafter), insufficient however to allow the shaft to disengage the bearings 34 and 35.

Housing 21 is provided with an exterior brack-

et 39 adapted to slidably receive and removably engage sheets of material 40, such as calendars, memoranda sheets, name plates, etc.

The ends 32 and 38, of housing 21, are provided with bearings 41 and 42, respectively, wherein a shaft 43 is operably mounted, the bearings 41 and 42 being in axial alignment with bearings 34 and 36. The end of shaft 43 which is engaged by bearing 41 is provided with a tongue 10 or clutch 44 which projects from the shaft 43, and bearing 41, and is adapted to engage the groove 37 of shaft 36, while the end of the shaft which is engaged by bearing 42 is provided with means 45, such as a wheel or crank, for manually rotating shaft 43 which in turn rotates shaft 36 when the latter shaft is pushed longitudinally, by the insertion of a pencil into the sharpener, into tongue-and-groove engagement with shaft 43.

On the inner face of the end 32, a non-rotatable cam sleeve 46, constituting a portion of the spring rewind reel 22, is mounted coaxially with bearing 41. This sleeve is provided with a coil type cam 47 on its inner walls, which cam is engaged by a cam follower 48 rotatably mounted upon the shaft 43. A coil spring 49, encircling the shaft 43, is attached at one end to the cam follower 48 and its other end is attached to a bearing provided member 50' rotatably mounted on the shaft 43 and fixed to one end of a spool sleeve 50 for rotatably mounting the sleeve coaxially upon the shaft 43 and free to rotate with respect to the ends 32 and 38. At least a portion of the bearing 41 is cylindrical and its outer surface serves as a bearing upon which one end of the spool sleeve 50 is rotatably mounted.

The spool 50 is intended as a drum or spool for a roll of material 51, such as blotting paper, memoranda paper, etc., which is intended to be withdrawn or unreeled, for use, through a longitudinal opening 52 in housing 21. The material to be wound upon the drum 50 is attached to an apron 53 which in turn is attached to the spool 50 by means of a flat spring clip 54 having transverse hooking means 55 adapted to pass through eyelets 56 in the apron (see Fig. 5) and engage the spool within holes provided therein. By flexing the spring clip 54 in a direction opposite the hooks 55 they may be withdrawn from the reel apertures and apron eyelets.

The material to be carried by the apron, and in turn reeled and unreeled from the spool 50, is attached in an overlapping manner to the free end of the apron by a banding clamp 57, as shown in Figs. 5, 9 and 10, which is comprised of a strip of spring steel having its ends bent sharply back upon its face-portion and terminating at a point slightly overlapping each other, whereby one end 60 may be hooked underneath the other. The clamp 55 may be opened by flexing the face portion of the clamp sufficiently to permit one end to pass from under the other. In order to provide additional frictional engagement between the apron, the sheet material, and the clamp, the face-portion 65 of the clamp is provided on its material engaging side with a raised portion adapted to fit within a depression or hole 58 in the bent back end portion of the clamp. The clamp 57 is of such length as will permit its longitudinal passage 70 through the opening or slot 52 in housing 21 in order that material clamped to the apron may be attached or replaced without removing the spool 50 from the housing 21, as will be described hereinafter.

The housing 21 is provided with a flat spring 59 attached at one end to the inner face of housing 21 and is retained in a flexed position by the inner walls thereof. The other end of the spring is provided with a transverse elongated member 60 5 adapted to be normally held, by the spring 59, unobstructingly along one edge of the housing slot 52 and adapted to be manually moved, laterally with respect to its normal position, across the opening of the slot 52 by further flexing the 10 spring 59 and for the purpose of gripping the material against the opposite edge of the slot 52 at any desired unreeled length. The spring 59 is manually flexed, for the purpose of bringing about the clamping action, by means of a stemmed button 61 attached to the spring 59 and passing through a shouldered or L-shaped slot 62 in housing 21. The clamp may be locked, in engagement with the material which passes through the slot 52, by a downward and thence slight horizontal movement of the button 61 whereby the stem thereof engages the shoulder forming the leg of the L-shaped slot. By a reverse horizontal movement the spring is freed and automatically carries the gripping member 60 back to its 20 normal position. The member 60 and the edge of the slot 52 may also have cutting or perforating characteristics if desired.

The sheet material carried by the spool 50 may also be provided at its exterior end with a clamp 30 63 similar to that of clamp 57, except that its length exceeds that of the slot 52, to prevent the material from escaping completely into the housing 21.

In the operation of the reel it will be understood from the foregoing that the spool sleeve 50 is adapted to receive the cam sleeve 46 as the cam sleeve 46 receives the cam follower 48. By this telescopic movement, of one into the other, the cam causes the cam follower to wind the spring 49. However to prevent an unwinding of the spring 49 by the otherwise rotary-free spool 50, to which the spring is attached, the spool must be held against rotation. This is done by first having the apron 53 attached to the spool 50 by 45 means of clip 54 and then by locking the apron by the clamp 60. The blotting paper or other material 51 is then clamped onto the protruding end of the apron 53 by means of clamp 57. The clamp 60 is then released by button 61 and the 50 spring wound reel is allowed to unwind and carry the material 51 onto the spool 50 by means of the apron 53. When the material 51 is unreeled, by pulling on clamp 63, the reel spring is rewound for the purpose of rewinding the material after 55 it has been withdrawn for use.

Having thus described my invention, what I claim is:

1. Reeling mechanism comprising a spool-sleeve rotatably mounted coaxially upon a shaft, 60 a non-rotatable tubular member adapted to be received coaxially upon one end of said shaft and coaxially within said spool-sleeve, a helical cam within said tubular member, a cam follower rotatably mounted coaxially upon said shaft and 65 adapted to engage said helical cam, a coil spring mounted coaxially upon said shaft having one end thereof attached to said cam follower and the other end thereof attached to said spool-sleeve, and means manually releasable for holding said 70 spool-sleeve against rotation.

2. A desk stand comprising a base member, a casing mounted thereon, said casing having end plates, a shaft passing through said end plates, a tubular member within said casing, said tubular 75

member being fixed on one of said end plates coaxially with the bearing therein, a helical cam within said tubular member, a spool-sleeve rotatably mounted coaxially upon said shaft and adapted to envelope said tubular member, a cam follower mounted rotatably and coaxially upon said shaft adapted to engage said helical cam, a coil spring mounted coaxially upon said shaft, said spring having one end thereof attached to 5 said cam follower and its other end attached to said spool-sleeve, and means for holding said spool-sleeve against rotation, said last means adapted to be manually engaged and whereby said spool-sleeve may be manually rotated against the 10 tension of said spring to unwind material on said spool-sleeve.

3. An article of manufacture comprising a base, a stationary casing mounted thereon, said casing having a longitudinal opening in the side 20 wall and having end plates, a shaft passing axially through said end plates, a coil spring mounted axially and rotatably upon said shaft and within said end plates, a spool-sleeve mounted coaxially and rotatably upon said shaft encompassing said 25 coil spring and engaging one end thereof, a stationary tubular sleeve provided with a helical inner cam, said tubular sleeve being mounted coaxially upon one end plate and adapted to be received into said spool-sleeve, a cam follower rotatable upon said shaft by said helical cam, said cam follower being attached to the free end of said coil spring, an apron attached to said spool-sleeve and adapted to extend through said longitudinal casing opening and be retracted by said 30 reel, releasable means on said casing for gripping said apron with its end projecting from said casing to hold the spool-sleeve against rotation.

4. In an article of manufacture comprising a spring rewind reel mounted coaxially and independently operable upon a shaft, mounting means for mounting said reel independently operable upon said shaft comprising a non-rotative cylindrical member mounted coaxially of said shaft and having an outer bearing surface for 40 operably retaining said reel thereon.

5. In an article of manufacture comprising a spring rewind reel mounted coaxially and independently operable upon a shaft, mounting means for mounting said reel independently operable upon said shaft comprising a non-rotative cylindrical member mounted coaxially of said shaft and having an outer bearing surface for operably retaining one end of said reel, and another bearing for said reel rotatably mounted upon said 50 shaft and fixed to the other end of said reel.

6. In an article of manufacture comprising a spring rewind reel mounted coaxially and independently operable upon a shaft, said spring rewind reel comprising a spool manually rotatable 60 and a spring opposing the manual rotation of said spool for reversely rotating the spool upon the release of torque manually applied thereto, mounting means for mounting said reel independently operable upon said shaft comprising a non-rotative cylindrical member mounted coaxially of said shaft and having an outer bearing surface for operably retaining said reel thereon.

7. In an article of manufacture comprising a spring rewind reel mounted coaxially and independently operable upon a shaft, said spring rewind reel comprising a spool manually rotatable and a spring opposing the manual rotation of said spool for reversely rotating the spool upon the release of torque manually applied thereto,

mounting means for mounting said reel independently operable upon said shaft comprising a non-rotative cylindrical member mounted coaxially of said shaft and having an outer bearing surface for operably retaining one end of said reel, and another bearing for said reel rotatably mounted upon said shaft and fixed to the other end of said reel. 5

8. In an article of manufacture comprising a spring rewind reel mounted coaxially and independently operable upon a shaft, mounting means for mounting said reel independently operable upon said shaft comprising a non-rotative cylindrical member mounted coaxially of said shaft and having an outer bearing surface for operably retaining one end of said reel, and another bearing for said reel rotatably mounted upon said shaft and fixed to the other end of said reel, said spring rewind reel comprising a spool manually rotatable and a spring held non-rotative at one 10 end with respect to said non-rotative cylindrical member and fixed at its other end in said rotatably mounted bearing. 15

9. An article of manufacture comprising a spring rewind reel and means for mounting the same independently operable upon a shaft mounted in a cylindrical member having an inner bearing surface for operably retaining said shaft, said spring rewind reel comprising a spool manually rotatable and a spring opposing the manual 20 rotation of said spool for reversely rotating the spool upon the release of torque manually applied thereto, said spring rewind reel mounting means comprising a bearing surface on the outer side of said cylindrical member for operably retaining one end of said reel and another bearing for said reel rotatably mounted upon said shaft and fixed to the other end of said reel. 25

10. An article of manufacture comprising a spring rewind reel and means for mounting the same independently operable upon a shaft mounted in a cylindrical member having an inner bearing surface for operably retaining said shaft, said spring rewind reel comprising a spool manually rotatable and a spring opposing the manual 30 rotation of said spool for reversely rotating the spool upon the release of torque manually applied thereto, said spring rewind reel mounting means comprising a bearing surface on the outer side of said cylindrical member for operably retaining one end of said reel and another bearing for said reel rotatably mounted upon said shaft and fixed to the other end of said reel, said spring being held non-rotative at one end with respect to said cylindrical member and fixed at the other 35 end in said rotatably mounted bearing. 40

11. Bearings and a shaft for mounting an independently operable spring rewind reel, one of said bearings comprising a cylindrical member fixed upon a support and having an inner bearing surface for operably retaining said shaft, said cylindrical bearing member also having means cooperating with said reel for holding one end of the spring of said reel and having an outer bearing surface for operably retaining one end of the 45 spool of said reel, and another of said bearings comprising a member fixed to the other end of said spool and having an inner bearing surface for rotatably mounting the same upon said shaft, said rotatably mounted bearing member also 50 having means for holding the other end of said spring. 55

JESSE L. COHEN.
